UNITED STATES PATENT OFFICE.

CHARLES J. KUMMER, OF SHEBOYGAN, WISCONSIN.

CHAIR-SEAT-SCOOPING MACHINE.

1,151,276.

Specification of Letters Patent. Patented Aug. 24, 1915.

Application filed January 7, 1914. Serial No. 810,847.

To all whom it may concern:

Be it known that I, CHARLES J. KUMMER, a citizen of the United States, residing at Sheboygan, in the county of Sheboygan and 5 State of Wisconsin, have invented new and useful Improvements in Chair-Seat-Scooping Machines, of which the following is a specification.

This invention relates to seat scooping 10 machines and the principal object of the invention is to so construct and connect the parts that the movement of the knives with relation to the seat will be synchronized with the feeding action, whereby each seat 15 will be uniformly scooped.

A further object of the invention is the provision of means for adjustably regulating the movement of the knives so as to accommodate the machine for different thicknesses of seats.

Still another object of the invention is the provision of means whereby the contour of the scooped out portion of the seat may be readily controlled or determined by 25 a novel arrangement of cam mounting which permits the cams to be inter-changed without providing additional support for the knife carrier and which insures accurate positioning of the cams.

30 Another object of the invention is the provision of novel means for regulating the feed of the chair seats to the knives.

Further objects of the invention will appear as the following description is read 35 in connection with the accompanying drawing which forms a part of this application, and in which:—

Figure 1 is an elevation of one side of the machine. Fig. 2 is a similar view of the 40 opposite side of the machine. Fig. 3 is an end view of the machine. Fig. 4 is a vertical longitudinal sectional view taken on the line 4—4 of Fig. 3. Fig. 5 is a top plan view. Fig. 6 is a vertical transverse sectional view on the line 6—6 of Fig. 1. Fig. 7 is a detail horizontal section on the line 45 7—7 of Fig. 3.

Referring more particularly to the drawing, 1 represents a work table which is supported upon a pair of leg frames 2 connected 50 together by the cross bars 3, 4 and 5. The leg frames have mounted thereon suitable bearings 6 and 7 in the former of which is journaled the driving shaft 8 having a pulley 9 loosely mounted upon one end and

provided with a clutch member which co-acts with a similar clutch member which is splined on the shaft and having an annularly recessed collar 11 to receive the yoke 12. This yoke is connected through a rod 60 13 to an operating lever 14 pivoted upon the leg 20 so that the feed which will be hereinafter described may be thrown out of or into gear when desired.

The opposite end of the shaft 8 is provided with suitable gears 15 which mesh with corresponding gears 16 upon the shaft 17 journaled in the bearings 7. This shaft carries a pair of hexagonal pulleys 18 which receive the feed chains 19, these feed chains 70 being continuous and passing over similar pulleys 20 carried by a shaft 21 journaled in bearings 22 slidably mounted in the guide-ways 23 and held in adjusted position by the set screws 24. Each chain travels in a longitudinal groove 25 formed in the table 1 and carries a predetermined number of raised lugs 26, the lugs being preferably arranged adjacent the rear end of each fourth link. However, it will be observed 75 that any other arrangement of lugs may be adopted and each link is preferably constructed to receive a lug so that the machine may be made to accommodate chair seats 80 of different widths or depths.

The shaft 17, as shown in Figs. 3 and 4, is supplied with a sprocket wheel 27 over which travels a sprocket chain 28 which connects the shaft 17 with the cam shaft 29. This cam shaft is passed through the leg frames 2 and is journaled in bearings 30 carried thereby. The shaft 29 is provided with a suitable sprocket wheel 31 to receive the chain 28. At the outer ends of the shaft 29 there is keyed to the shaft suitable sleeves 32 having lateral projections 33 which are adapted to fit in recesses 34 formed in the actuating cams 35. These cams are preferably secured to the sleeves by bolts 36 so that they may be removable to change the 95 throw of the mechanism which they control, as will be hereinafter described.

Mounted on the outside of the leg frames are suitable guiding members 37 in which are slidably mounted what may be termed 105 the knife carriers 38. These knife carriers are in turn provided with guide-ways 39 in which the adjusting plates 40 are slidably mounted. The plates 40 are slotted at 41 and passing through the slot is a clamping 110

bolt 42 which holds the plates firmly against the knife carriers, as will be readily understood, the plates themselves being adjusted longitudinally of the knife carriers by means 5 of set screws 43 which are threaded in the lugs 44 formed integrally with the knife carriers. The lower end of each plate 40 carries a stub shaft upon which a cam engaging roller 45 is journaled. These rollers 10 are adapted to engage the cams 35 to form anti-friction and adjustable engagement between the cams and the knife carriers. Each knife carrier is provided with a pair of bearing ears 46 between which is pivoted a bearing 47 adapted to receive one end of the knife shaft 48 and this shaft carries suitable knives 49 which scoop out or carve the chair seats in accordance with their formation or outline. Both of the knife carriers 15 are normally held depressed by springs 50 which engage the carriers at one end and at the opposite end are contacted by adjusting screws 51 carried in the cross bars 52 which are secured to the standards 53. These 20 standards are arranged upon opposite sides of an opening 54 formed in the table 1 to permit the passage of the knife carriers and also form a guide for the feed roller bearings 55 in which the feed or pressure rollers 25 56 are journaled, the latter bearings being held in position against adjustable stops 57 by the springs 58.

The construction of the knives and their 30 associated parts are well known in the art and need not be described more fully. It is sufficient to state that the shaft 48 is independently driven and that it carries a pulley for the reception of the independent belt which drives the knives at their high speed 40 and in a direction reverse to the feed of the seat.

Extending above the table are suitable standards 59 which hold the seats in stack form, as will be readily understood. Attached 45 to one of these standards and to a relatively short standard 60 upon the opposite end of the table is a gate supporting frame comprising two bars 61 upon which are slidably mounted the gate members 62 50 slotted longitudinally to receive the clamping bolts 63. These gate members may be adjusted toward and away from the table so that the machine will be adaptable for work upon seats of different thicknesses, it 55 being understood that the seats are removed

from the bottom of the stack in order and fed to the knives 49.

It will be noticed that as the feed chain shaft 17 is connected directly through the chain 28 to the cam shaft 29 that the movement of the knife carriers is always synchronized with relation to the feed, thus insuring a uniform and even cut of each seat. When it is desired to change the cams the cam shaft is rotated until the projections 33 on the sleeves are brought into contact with the rollers 45. The bolts 36 may be then removed and new cams supplied without the necessity of using any auxiliary mechanism to support the knife carriers against the 65 tension of the springs 50.

In the operation of the device chair seats are stacked upon the table against the standards 59 and gate pieces 62, the latter being adjusted so as to permit the passage of a 75 single seat of the thickness of seats being worked upon. The machine is then started into operation by throwing in the clutch. As each pair of lugs comes into engagement with the chair seat it is carried forwardly 80 beneath the rollers 56 and the knives 49. Simultaneously with this action the cam shaft shifts opposite ends of the knife shaft in accordance with the scoop desired, the seats being projected from the rear end of 85 the machine as they are acted upon.

What is claimed is:—

In a chair seat scooping machine, a support, a feed table carried thereby, bearing carriers slidably mounted upon the supports 90 on opposite sides of the table, bearings pivoted in said carriers, a knife shaft journaled in the bearings, means for feeding the work over the table continuously beneath the knives, said means including a driving shaft, 95 a shaft driven by the driving shaft, sleeves secured upon the latter shaft and having lateral projections, notched cams fastened to said sleeves and projections, adjustable plates mounted on the carriers and adapted 100 to engage the cams, said cams being freely removable from the sleeves when the plates are in engagement with the lateral projections.

In testimony whereof I affix my signature 105 in presence of two witnesses.

CHARLES J. KUMMER.
